DESIGN FOR A HANDBAG OR THE LIKE

Moe J. Cohen, New York, N. Y.

Application September 24, 1945, Serial No. 122,281

Term of patent 3½ years

(Cl. D87—3)

To all whom it may concern:

Be it known that I, Moe J. Cohen, a citizen of the United States of America, residing in New York city, county of New York, and State of New York, have invented a new, original, and ornamental Design for a Handbag or the like, of which the following is a specification, reference being had to the accompanying drawing, forming part thereof, wherein

The rear of the handbag or the like is substantially the same in appearance as the front.

I claim:

The ornamental design for a handbag or the like, substantially as shown and described.

MOE J. COHEN.
